CLAIM

The ornamental design for a photographic camera or similar article, as shown and described.

DESCRIPTION

FIG. 1 is a top and left front perspective view of a photographic camera or similar article showing my new design;

FIG. 2 is a left side elevational view thereof;

FIG. 3 is a top and left front perspective view of another embodiment of my new design of FIGS. 1 and 2;

FIG. 4 is a left side elevational view thereof;

FIG. 5 is a bottom and left rear perspective view of both embodiments;

FIG. 6 is a rear elevational view of both embodiments.
